UNITED STATES PATENT OFFICE

FRANK L. MORSE, OF ITHACA, NEW YORK

AUTOMATIC GARAGE DOOR

Application filed December 16, 1929. Serial No. 414,531.

This invention relates in general to automatic door operators, such as are used on garages, cars, factories, and other structures, and is particularly applicable to doors of the folding or leaf type. The invention has for its objects the provision of a simple and effective apparatus which can be readily adapted to various installations, and to doors of different sizes. Another object is to provide a type of drive and linkage connection which will positively control the opening and closing of folding doors without jamming at any point and without depending on the momentum of the doors to carry the motion thru. Various other objects will become apparent as the description proceeds.

Referring now to the drawings forming part of this specification,

20 Fig. 1 is a plan view of a pair of folding doors and the operating mechanism, it being understood that where there are two pairs of such doors the adjacent pair is similarly equipped.

25 Fig. 2 is a corresponding elevation—the doors being shown closed in both Fig. 1 and Fig. 2.

Fig. 3 is a plan view similar to Fig. 1 but showing the doors partly open, (in full 30 lines), and showing their position when fully open in dotted lines.

Fig. 4 is a detail view, partly in section, showing the manner of connecting the operating link to the door.

35 Fig. 5 is another detail view, showing the supporting arm and roller attached to the door.

Referring first to Fig. 1 and Fig. 2, the walls of the garage or other structure having the doors to be operated are indicated by the reference numeral 1, and a pair of folding doors attached thereto are indicated by the reference numerals 2 and 2', the door leaf 2 being hinged to the wall structure 40 at 3, and the second leaf 2' being hinged to

the first leaf 2 at the points 4, in the customary manner of folding doors. There are usually two pairs of such doors in a doorway, but as the other pair are similar, they are only indicated in a fragmentary manner, 50 as at 2''. The weight of such doors is usually supported in part from a rail 5 on which runs a trolley 6, the trolley wheel 6 being pivotally attached at 7 to a bracket arm 8 which is in turn pivotally attached at 9 to the outer leaf of the door 2', as shown more in detail in Fig. 5. The structure just described is merely that usually found in a typical folding door.

To operate the doors a link or arm 10 is 60 connected to the second leaf 2', as shown in the general views of Fig. 1, Fig. 2 and Fig. 3, and also shown more in detail in Fig. 4. This link 10 is pivotally attached to the door leaf 2' by the bracket 11, and the other end of the link 10 is attached to a driving chain 12 and is guided by rollers 13 and 13' which run in tracks or grooves 14 and 14' extending parallel to the driving strand of the chain 12. These tracks 14, 14', like 70 the track 5, are preferably supported by attaching them to the ceiling of the building, or to the walls or other fixed parts of the structure.

The chain 12 runs around sprockets 15 and 16, the sprocket 15 being mounted on the motor base 17, and the sprocket 16 being mounted on a bracket 18 which may be attached to any convenient part of the structure 1. The ends of the chain 12 are usually 75 connected by a coil spring 20 which maintains a proper tension, and also permits a certain variation in the location of the bracket 18. If the adjustment provided by the spring 20 is not enough, the length of 80 the chain 12 can readily be changed by adding or subtracting a few links, so that the apparatus can be readily installed in 85 garages or other structures of various dimensions.

The sprocket 15 is driven by the reversible electric motor 22 operating thru the worm 23 and worm wheel 24, which is keyed to the same shaft as the sprocket 15. The 5 motor 22 also drives a similar mechanism for the other pair of doors, which as it does not differ in principle, is only indicated fragmentarily, by the reference numerals 12', 15', and 24'. The motor 22 is mounted 10 on the motor base 17 which is secured to any suitable fixed portion of the building, usually by rods or brackets, or it may be built into the building at the time it is constructed. The electric circuits, switch 15 mechanisms, etc., for operating the motor 22 may be of any of the numerous types commonly used in door operators for starting, stopping and reversing the motor, and as they are well known, need not be further 20 described here, in as much as the present invention is more particularly concerned with the operating mechanism between the motor and the doors.

When the doors are closed, as shown in 25 Fig. 1, the arm or link 10 is approximately perpendicular to the door 2' and track 14, so that the door is locked or wedged in its closed position against any attempts to open it by pressure from the outside. Before the 30 doors can be opened by pressure from the outside the hinge 4 must bend inward, and as shown in Fig. 1, any such inward force or pressure is transmitted thru the arm 10 directly to the fixed track 14,—the arm 10 being 35 so nearly perpendicular to the track 14 that little strain is put on the chain 12, and the doors are easily held firmly in the closed position.

When the motor 22 is energized to open 40 the doors, turning the sprocket 15 in the direction indicated by the arrow, the initial movement of the chain 12, to which the arm 10 is attached, gives a relatively slow or gradual starting movement to the door leaf 2', owing to the fact that the arm 10 is 45 substantially on or near a dead center position. On the other hand, though the initial motion is slow, it has a powerful leverage and imposes but little starting load on the 50 motor 22,—which is very important in such installations, as only small motors are desirable in private or residence installations, yet the power must be sufficient to cope with frozen and sticky doors, snow, etc.

55 As the movement of the chain 12 continues, the movement of the doors increases more rapidly, and the arm 10 swings across the top of the door 2', as shown in full lines in Fig. 3, so that the continued movement 60 tends to fold back the leaf 2' against the leaf 2, as indicated in dotted lines in Fig. 3. The motion usually travels a little over beyond that point, so that the roller 13 runs part way around the back of the sprocket 16,— 65 approaching a dead center position so that

the doors come to a stop gradually when the motor 22 is cut off, and relieving the mechanism from shock. This also permits the doors to start gently on the return reverse movement.

70 When the doors are to be closed the motor 22 is of course reversed, and the operation occurs in the reverse manner, with the link 10 first opening the doors into a V and then flattening them against the door frame. At 75 the close the arm 10 is at or near the dead center position, as before, so that slight variations in the time that the motor 22 shuts off do not materially affect the operation of the mechanism, and the door motion slows 80 down gradually.

In the opening and closing of folding doors considerable difficulty has heretofore 85 been experienced due to the fact that two types of motion are really involved,—the first to break the doors into a V so that they can be moved laterally, and the second to fold them laterally out of the way. The 90 transition from one of these motions to the other has generally caused difficulty. In the 95 present invention, the kinematic properties of the mechanisms described are such that there is always a sufficient component of force in the direction of the motion desired, and jamming and sticking are minimized.

While I have in the foregoing described 100 a particular installation as a typical embodiment of the invention, it will be understood that it is merely by way of illustration to show the principles thereof, and that the invention is not limited to the particular details shown, but is subject to various modifications and adaptations in different installations as will be apparent to those skilled 105 in the art, without departing from the scope 110 of the invention which is set forth in the following claims.

I claim:

1. In a door operating mechanism, the 115 combination of a doorway structure, a first door leaf hinged to said structure, a second door leaf hinged to said first door leaf, an arm pivotally attached to said second door leaf, a drive chain attached to said arm, said arm and chain extending over the top of 120 said doors as the doors are folded, and motor means for operating said chain to open and close the door.

2. In a door operating mechanism, the 125 combination of a pair of folding doors, an arm pivotally attached to the second leaf of said doors and arranged to extend substantially straight back from said doors when the doors are closed and to swing over the top of the doors when they are open, a drive chain attached to said arm and extending over the doors when they are open.

3. In a door operating mechanism, the 130 combination of a doorway structure, a first door leaf hinged to said structure, a second

door leaf hinged to the first door leaf, an arm pivotally attached to said second door leaf, a drive chain attached to said arm, a roller on said arm, guide means for said 5 roller extending in the direction of the drive chain, said arm, chain and guide means extending over the top of the doors as the doors are folded, and motor means for operating said chain to open and close the 10 door.

4. In a door operating mechanism, the combination of a doorway structure, a first door leaf hinged to said structure, a second door leaf hinged to the first door leaf, an 15 arm pivotally attached to said second door leaf at a point nearer the hinged edge of said leaf than the free edge, said arm being arranged to swing over the top of the door leaves as they are folded open, and 20 means for moving the swinging end of the arm along a rectilinear path at a slight angle to the plane of the doorway.

5. In a door operating mechanism, the combination of a two leaf folding door section, a sprocket near the free end of the 25 second leaf, a second sprocket near the fixed hinged end of the first leaf, an operating arm pivotally attached to the second leaf adjacent the hinged edges of said leaves, a 30 drive chain attached to said arm and running over said sprockets, guide means for the chain end of said arm extending along the direction of the chain, and motor means for operating said chain to open and close 35 the door.

6. In a door operating mechanism, the combination of a doorway structure, a first door leaf hinged to said structure, a second door leaf hinged to the first door leaf, an 40 arm pivotally attached to said second door leaf at a point nearer the hinged edge of said leaf than the free edge and arranged to extend backwards from the door when the door is closed, means for moving the other 45 end of the arm laterally and towards the side of the doorway to open the door first with an oblique pull and then with a substantially direct pull, the arm being sufficiently short and the path of the moving 50 means sufficiently close to the doorway so that the arm swings from a backward to a lateral position in the process of opening the door and passing over the tops of the door leaves folds them back against the side.

55 7. In a door operating mechanism, the combination of a doorway structure, a motor mounted substantially over the middle of said structure, a worm driven by said motor, a pair of worm wheels driven by said 60 worm, a pair of folding doors each having two leaf sections, a pair of chain drives driven by said worm wheels respectively and extending laterally over the tops of the doors when open, a pair of operating arms 65 pivotally attached to the second door leaves

respectively at one end and to the chain drives respectively at the other end, guide rollers on said arms near said other ends, and guide tracks extending along in the direction of the chain drives, said arms swinging over the tops of the door sections as 70 they are folded open.

In witness whereof I have hereunto set my hand this 26th day of November, 1929.

FRANK L. MORSE.
